VACUUM CLEANER NOZZLE

Charles T. Fromknecht, Anderson, S.C., assignor to Westinghouse Electric Corporation, East Pittsburgh, Pa., a corporation of Pennsylvania

Filed Dec. 31, 1964, Ser. No. 422,808

2 Claims. (Cl. 15—400)

This invention relates, in general, to vacuum cleaners and, more particularly, to a nozzle attachment for use therewith.

Most nozzle attachments employ brushes since suction alone will only remove a portion of the dirt and lint from a carpet or upholstered furniture. One common type of attachment is provided with a single length of brush mounted on the nozzle transverse to the normal direction of movement thereof. The dirt which is dislodged from the carpet by the brush is sucked into a centrally disposed chamber from the inlet opening in the nozzle, portions of the inlet opening and chamber being in front of the brush and a portion in back of the brush. An arrangement such as this, at first, appears to be efficient in that suction is provided at the front of the brush for carrying away dust which is normally pushed forward by the brush and suction at the rear of the brush for carrying away dust which passes under the brush. However, this arrangement is not desirable because string-like objects tend to wrap around the brush from both sides and become entangled one end with the other. Also, suction is not adequate along the entire length of the brush, it being somewhat concentrated toward the center of the nozzle. Furthermore, it will be understood that an arrangement of this type is not desirable for cleaning curtains, draperies or the like because of the concentrated suction.

Another common type of nozzle attachment is provided with an oval-shaped brush attached to the periphery of the inlet opening of the nozzle. These nozzles have a distinct drawback in that the forward portion of the brush sweeps most of the dirt in front of the nozzle such that the suction has little or no effect on picking up the dirt. Consequently, the only dirt that is picked up is that which manages to pass underneath the forward portion of the brush and that which is loosened by the rearward section of the brush.

Accordingly, it is the general object of this invention to provide a new and improved nozzle attachment for a vacuum cleaner.

It is a more particular object of this invention to provide a new and improved nozzle and brush construction which minimizes entanglement of string-like matter around the brush element.

Another object of this invention is to provide a new and improved nozzle which is suitable for cleaning lightweight objects such as curtains and draperies.

Still another object of this invention is to provide a new and improved brush nozzle which is simple in construction and in which mounting of the brush is readily accomplished without the use of fasteners or the like.

Briefly, the present invention accomplishes the above cited objects by providing a nozzle attachment having a flexible body portion with an interior chamber through which the dust-laden air passes. A brush assembly comprising a flat orifice plate having a plurality of staggered slots in the longitudinal edges thereof is readily insertable in a peripheral slot in the interior of the flexible body portion through manipulation of the body portion. A substantially U-shaped channel member is secured to one surface of the orifice plate, coextensive with the longitudinal axis thereof, and is adapted to removably support a cleaning brush for dislodging dirt from a surface being

2

cleaned. The brush is disposed intermediate the slots so that dirt pushed forward by the brush will be sucked through certain of the slots while dirt passing under the brush will be sucked through certain other slots on the opposite side of the brush. The staggering of the slots serves to distribute the suction at different points along the longitudinal axis of the nozzle thereby rendering the nozzle more efficient for cleaning draperies, curtains or the like. Furthermore, the staggering of the slots with respect to the centrally disposed brush minimizes entanglement of string-like objects completely around the brush. This is because a portion of the orifice plate lies adjacent the brush opposite from each of the slots preventing at least one end of the string from wrapping around one side of the brush. The ends of the string, with this arrangement, cannot become entangled with each other, it being possible for the string-like object to eventually become dislodged and sucked into the chamber of the nozzle.

Further objects and advantages of the invention will become apparent as the following description proceeds and features of novelty which characterize the invention will be pointed out in particularity in the claims annexed to and forming a part of this specification.

For a better understanding of the invention, reference may be had to the accompanying drawings, in which:

FIGURE 1 is a bottom plan view representing one embodiment of the invention;

FIG. 2 is a bottom plan view of the brush holder and orifice plate; and

FIG. 3 is a cross-sectional view taken on the line III—III of FIG. 1.

Referring to the drawings, especially FIGS. 2 and 3, reference character 10 designates generally a vacuum cleaner nozzle attachment comprising a generally rectangular body portion 11 and a connector tube 12 rotatably and removably supported in an integrally formed enlarged housing portion 13, extending rearwardly of the body portion 11. While the body portion 11 may be made from any suitable material, it is preferably molded from a flexible plastic for a purpose which will herein-after be explained.

The body portion 11 comprises a pair of longitudinal walls 14 joined integrally at their extremities by a pair 45 of transverse walls 16 and at the top with a wall 17 to form a chamber 18 internally of the body portion, which chamber communicates with an open face or inlet opening 19 opposite the top wall 17. The inner surfaces of the longitudinal and transverse walls are provided with 50 a substantially continuous slot or groove 21 which serves to mount a brush assembly 22 (FIGS. 1 and 3).

The brush assembly 22, made from any suitable material, for example, plastic, comprises a flat generally rectangular orifice plate 23 having a plurality of staggered 55 slots or openings 24 in the longitudinal edges thereof which serve as air passageways from the inlet 19 to the chamber 18. The assembly 22 further comprises a resilient U-shaped channel member 26 secured to the plate 23 in a manner adapted to support a cleaning brush 27 such that the cleaning brush can easily be removed. The channel member, and, therefore, the brush are positioned intermediate the slots and are coextensive with the longitudinal axis of the plate 23. It will be understood that by locating the brush intermediate the slots, the dirt which 65 is pushed in front of the brush will be sucked into the chamber 18 through the slots adjacent that side of the brush while the dirt which passes under the brush, toward the rear of the nozzle, will be drawn through the slots adjacent the opposite side of the brush. As can be seen in FIG. 1, the slots lie adjacent one side or the other of the brush and opposite a portion of the plate 23. This arrangement prevents string ends from simultaneously

wrapping around the brush from both sides thereof and becoming entangled one end with the other thereby allowing the string picked up by the brush to eventually become dislodged and pulled into the chamber 18 through one of the slots 24. As mentioned hereinbefore, body portion 11 is preferably molded from a plastic material. This enables the edges of the plate 23 to be readily inserted into the groove 21 by manipulating the ends of the flexible body portion 11.

It can be seen that the brush nozzle herein disclosed, due to the staggered arrangement of the slots, lends itself to cleaning draperies, curtains or the like. Ordinarily brush nozzles of the type herein contemplated are provided with a centrally disposed chamber, consequently, the concentrated suction produced by such an arrangement has a tendency to suck the fabric into the inlet. This is not the case where the suction is distributed along the face of the nozzle contacting the face being cleaned. Moreover, by distributing the suction in this manner, a more efficient nozzle is produced. Utilization of the nozzle for this purpose is facilitated by removal of the cleaning brush which, as stated hereinbefore, can be readily removed.

While there has been shown and described what is at present considered to be the preferred embodiment of the invention, modifications thereto will readily occur to those skilled in the art. It is not desired, therefore, that the invention be limited to the specific arrangements shown and described and it is intended to cover in the appended claims all such modifications as fall within the 30 true spirit and scope of the invention.

What is claimed is:

1. In a nozzle for a vacuum cleaner having a suction

5

device, in combination, a flexible body portion having a generally elongated open face portion and provided interiorly with a vacuum chamber and having a peripheral groove in the walls thereof in the area of said chamber, an orifice plate insertable in the peripheral groove, a brush support extending longitudinally of said orifice plate and secured thereto, said orifice plate being provided with peripheral notches in the longitudinal edges thereof, said notches cooperating with the walls of said flexible body portion to provide an air inlets to said vacuum chamber, said notches being staggered with respect to the longitudinal axis of said orifice plate whereby suction is distributed across the entire surface of the nozzle and a brush in said support.

2. Structure as specified in claim 1, wherein said brush is removable from said brush support for facilitating utilization of the nozzle on draperies or the like.
